ANIMAL SHELTER

Alan E. Gilstrap, 519 Clarice Ave.,
Charlotte, N.C. 28204

Filed Feb. 23, 1971, Ser. No. 118,207

Term of patent 14 years

Int. Cl. D30—02

U.S. Cl. D30—1

Fig. 2

Fig. 3

Fig. 4

Fig. 5

Fig. 6

FIG. 1 is a front, top and right side perspective view of an animal shelter, showing my new design;

FIG. 2 is a front elevational view;

FIG. 3 is a left side elevational view the right side being substantially a mirror image thereof;

FIG. 4 is a rear elevational view;

FIG. 5 is a top plan view; and

FIG. 6 is a bottom plan view thereof.

I claim:

The ornamental design for an animal shelter, as shown and described.
